RECTIFIER.

Application filed July 18, 1923. Serial No. 652,268.

This invention relates to rectifiers and is particularly directed to constant current rectifiers.

Rectifiers have heretofore been produced which rectify alternating current but these devices have not proven satisfactory for supplying devices which require a non-fluctuating direct current at absolutely constant voltage, such as the plate circuit of vacuum tubes for transmitting or receiving wireless messages, the filament of such tubes, the electromagnets of loud speakers, or other devices which require a supply of electric energy of constant intensity. These rectifiers as heretofore constructed have not been suitable for direct connection to alternating current lighting mains for supplying electric energy of unvarying intensity. Further, these devices, if of the thermionic type have been of relatively short life, inefficient, require a large internal voltage drop, and have been bulky and cumbersome.

This invention is designed to overcome the above noted defects and has for its primary object the provision of a constant current rectifier which is adapted to be directly connected to an alternating current supply system and to furnish direct current of uniform and non-fluctuating value.

Further objects are to provide a rectifier adapted to furnish electrical energy of unvarying value which is certain in its functioning, which has a low internal voltage drop, which is efficient, which has an increased life, which is heated by alternating current, and which is compact.

Further objects are to provide an equi-potential cathode, to provide for the heating of such cathode by radiation, conduction, or both, as by means of a filament or resistance heater.

Further objects are to provide means for keeping the temperature of the main cathode constant and for keeping it at equal potential throughout its entire active surface although it is heated by alternating current, and to provide a device in which substantially all the energy supplied for heating the cathode is usefully employed and losses are reduced to a minimum.

Further objects are to provide as a unitary device, a rectifier and a thermionic apparatus for holding the rectified current at a constant value, in which the same or different heaters may be used for the rectifier and

filter or current limiting device, and to provide a system employing this unitary device in such a manner that constant current of any desired value may be obtained.

Embodiments of the invention are shown in the accompanying drawings, in which:

Figure 1 is a set of curves illustrating the voltage and current values in rectifying devices.

Figure 2 is a set of curves illustrating the relation between plate current and the plate voltage of certain thermionic devices.

Figure 3 is a diagrammatic view of one form of the apparatus having certain connections inside the tube.

Figure 4 is a diagrammatic view of one form of the apparatus in which the cathodes of the rectifier and current filter are heated by independent auxiliary cathodes or heaters.

Figure 5 is a view showing the cathodes heated by a common heater.

Figure 6 is a view illustrating the mechanical construction of one form of device such as illustrated in the diagrammatic views.

Figure 1 shows a set of curves plotted with time as the abscissas illustrating the action of a rectifier, and will first be described. In the figure the curve A shows an alternating current, and in dotted lines the unused portion when one half of each of the waves is rectified. Curve B shows the value of the rectified current, which may be smoothed out to a certain extent by means of condensers, choke coils and similar devices and made to assume the shape shown at C. The corresponding voltage curve is shown at D, for this partially smoothed out current with the maximum and minimum voltages indicated by $E_{\max}$ and $E_{\min}$ and the variation voltage or difference indicated by E_d .

It is highly desirable in certain kinds of work, particularly radio work, to obtain a practically constant current from alternating current supply mains, and in this work even minute fluctuations must be avoided. I, therefore, propose to combine with a rectifier, such as a thermionic rectifier, a current filter or limiter of the thermionic type. This current filter or limiter I combine with the rectifier as a single unitary device, and I have found that when desirable the same or different means may be employed for heating the cathodes of both devices. I therefore combine with the rec-

ifier a thermionic current filter to which I apply the pulsating unidirectional voltage from the rectifier in a manner to saturate the thermionic current filter at the minimum voltage supplied thereto.

Figure 2 shows at Y the characteristic curve for a thermionic device in which the plate voltage is plotted as the abscissas and the plate current as the ordinates. The dotted line W shows the curve for an ideal thermionic device. The curve X shows the characteristics of my thermionic filter and I have found that it closely approximates the ideal curve as shown in Figure 2. The values of E_{max} , E_{min} , and E_d have been plotted to a larger scale than in Figure 1 for the sake of clearness. It will be seen that the minimum voltage, E_{min} , is greater than the critical voltage E_c at which saturation begins and that, therefore, the variation between E_{min} and E_{max} has no varying effect upon the plate current and that the plate current is, therefore, constant.

Figure 4 shows one way of practicing the invention. The alternating current mains 1 and 2 are connected to the primary 3 of a transformer. The secondary 4 of the transformer supplies the plate current for a compound thermionic device. This device consists of an evacuated vessel 5 which may be either partially or wholly divided into two compartments by a suitable partition 6. Two filaments 7 and 8 are connected with the mains 1 and 2 through suitable independent rheostats 9 and 10. The device is equipped with cathodes 11 and 12 which are heated by radiation from the filaments 7 and 8 respectively to a uniform temperature. They are preferably composed of tungsten, nickel, molybdenum, or similar metal, and are preferably coated on the side towards the filaments with a nickelous oxide. On the side towards the plates they are preferably coated with an oxide having a low electron affinity such as barium, strontium, thorium, or calcium oxide to increase their electron emission. Plates 13 and 14 are arranged in close proximity to the cathodes and accurately parallel them.

50 The upper device indicated generally at R in the form shown, is the rectifier and its anode or plate 13 is connected to one side of the secondary. Its cathode 11 is connected by means of the conductor 15 with the anode of the current filter or thermionic limiting device which is the lower device in the form shown and indicated generally at F. The cathode 12 of the filter is connected to the positive output terminal 16. The other output terminal 17 is connected to one side of the secondary 4 of the transformer by means of the conductor 18. If desired, a condenser 19 may be bridged across the conductors 15 and 18 to partially smooth out the pulsations from the rectifier before reaching the

current limiting device, by storing up energy during a pulse and giving it back after the pulse has passed.

The operation of this form of the apparatus is as follows:—The main cathodes 11 and 12 are heated by radiation, conduction, and if either compartment is gas filled, by convection. The filament construction is such, as will be described in connection with the mechanical details, that although it is heated by alternating current, the cathode is maintained at a constant, non-fluctuating temperature, and the electron emissive power of the cathodes does not vary. Obviously, the actual current flowing through the rectifier varies, that is to say, comes in pulses, but the current through the filter is of a steady and unvarying value. Consequently the current supplied the work circuit (not shown) from the terminals 16 and 17 is unvarying.

Figure 3 shows a construction similar to that shown in Figure 4, with the exception that the filaments are connected in series by means of the conductor 38 inside of the vessel, and that the cathode 11^a of the rectifier, is connected to the anode 14^a of the current limiting device by means of the conductor 45, located inside the vessel. The same numbers have been used as in Figure 4, as far as possible, with the exception that suffixes are added to certain of the reference characters. The mechanical construction of this tube is illustrated in Figure 6, which will be described in detail hereinafter.

Figure 5 shows a form of the device in which the rectifier R is provided with two plates 20 and 21 connected to opposite terminals of the secondary 22 of the transformer. The center point of the secondary is connected through conductor 28 to a choke coil 23 and from thence to the negative terminal 17. The cathode 24 is connected by means of the conductor 25 with the anode 26 of the current filter F. A condenser 27 is bridged across the conductors 25 and 28 and partially smooths out the fluctuations before they reach the current limiting device or filter F. The cathode 29 is connected to the positive delivery terminal 16 and if desired a condenser 30 may be bridged across the terminals 16 and 17.

The operation of this apparatus is substantially the same as that apparatus illustrated in Figure 4, except for the action of the choke coil 23 and condenser 30, and the double anode of the rectifier. One or the other of these anodes 20 and 21 is passing current to the cathode 24 for each pulse of the alternating current. In this manner a more nearly constant supply of energy is furnished by the rectifier before it is finally smoothed out by the current filter.

Figure 6 shows the mechanical construction of the apparatus illustrated diagram-

matically in Figure 3 in which separate filamentary heaters are provided for each of the main cathodes of the current filter and current rectifier and are connected in series 5 within the vessel. In the description of this figure as far as possible suffixes will be added to the reference characters indicating the corresponding parts in the diagrammatic figure so that comparison of the illustrations 10 may be most readily made.

The evacuated vessel 5^a may take the form of the usual bulb, such as employed in vacuum tube work and may be provided with a cylindrical base 33 equipped with a plurality 15 of prongs 34 electrically connected to the different portions of the device.

The partition 6^a may or may not extend completely across the apparatus. In the form shown in Figure 6 it extends only partly 20 across and does not hermetically seal on separately the two portions of the device. The partition is carried in a recess formed in the porcelain or other similar type of main support 35 which is suitably carried by 25 a glass or other type of pillar 36 from the lower portion of the apparatus. This porcelain support 35 is provided with a set of helical grooves which carry the filament 8^a of the filter and the filament 7^a of the rectifier. One terminal of the filament 8^a is 30 connected to the end of the conductor 37 and its other end is connected to one end of the filament 7^a. The upper end of the filament is connected by means of a conductor 38 which extends upwardly out of the porcelain main support 35 and joins the 35 downwardly extending conductor 39 which passes centrally through such main support 35 and through the pillar 36. This figure, 40 it will be seen, differs slightly from Figure 4 in the arrangement of filaments, that is to say, while the filaments have been shown in parallel in Figure 4 they are shown in series in this figure. Obviously though, 45 either arrangement could easily be made in a simple and readily appreciated manner. The main support 35 is provided with flanges 40 at its upper and lower ends and with a central flange which is provided with 50 a slot and receives the partition 6^a. Upon these flanges, the cathode 12^a of the filter and 11^a of the rectifier rest. This main support and the associated electrodes may be of any desired shape and in the form shown 55 is roughly oval shape. The plate 13^a of the rectifier is spaced from the cathode 11^a thereof and is carried by relatively rigid conducting supports 41 which are carried by the upper end of the insulating support 42 60 through which the conductor 43 is passed. This conductor is electrically connected to the stiff wires 41 and to one of the prongs.

The plate 14^a of the filter is spaced from the cathode 12^a thereof and is carried by 65 means of relatively stiff supports 44, one of

which may be connected by means of conductor 45 with the cathode 11^a of the rectifier and with one of the prongs. This last conductor may extend downwardly from the metal supports 46 of the plate 70 13^a and through the insulating glass pillar. It corresponds to the conductor 15 in Figure 4.

It is to be noted that accurate parallelism of the plates and cathodes in the two portions of the device may be most readily attained and that the spacing of such portions may be extremely small if desired thus correspondingly varying and improving the electrical characteristics of the device. It is 75 further to be noted that all of the energy from the filaments is transmitted to their cathodes either by radiation or conduction, and that even the light which is radiated from the filaments, when luminous filaments 80 are employed, is transformed into heat in the cathodes and is prevented from escaping from the device. This obviously, improves the electrical efficiency of the apparatus.

Obviously, various other mechanical embodiments of the invention may be employed but it is thought that the selection described will illustrate in a clear way the different modes which may be followed in a physical embodiment of the device. It is intended 90 that the current filter shall be a high vacuum apparatus in all forms of the invention.

It is to be noted that the relatively heavy porcelain or other type of support for the filaments acts in the manner of a fly wheel 100 so to speak in that it stores up a material quantity of heat and prevents any fluctuation of heat from the filaments from varying the temperature of the corresponding cathodes. This massive construction is 105 extremely effective in its functioning and aids in maintaining a uniform temperature for the cathodes.

It is to be noted that in each of the several forms of the device that the cathode of the filter is an equipotential surface and is heated by an auxiliary means energized from alternating current. It is also to be noted that the temperature of the main cathode of the filter remains constant and does not 110 follow the fluctuations due to the alternating current. It is to be further noted that this type of cathode may be also employed in a number of the rectifiers which are combined with the filter.

If it is found desirable the coiled filament may have its halves or different portions, wound in opposite directions to avoid any transformer action from such filament.

It is to be further noted that by employing the plate type, either flat or curved, of anode and cathode that exact parallelism of the parts may be assured. This is particularly desirable in the current filter or current limiting device.

It will further be seen that a constant current rectifier has been provided which is adapted for energization from alternating current and which will supply a constant direct current of non-fluctuating value.

Although certain embodiments of the invention have been described with considerable detail, it is to be understood that the invention may be variously embodied and is, therefore, to be limited only as claimed.

I claim:

1. A unitary combined rectifier and current limiting device for supplying unidirectional constant value current from alternating current, comprising an evacuated vessel, a pair of supporting members located within said vessel, a heating filament wound upon each of said members, a cathode surrounding each of said members and heated by the corresponding filament, and an anode surrounding each of said cathodes and spaced therefrom, said members being bodily separate and distinct.

2. A unitary combined rectifier and current limiting device for supplying unidirectional constant value current from alternating current, comprising an evacuated vessel, a pair of supporting members located within said vessel, a heating filament wound upon each of said members, a cathode surrounding each of said members and heated by the corresponding filament, an anode surrounding each of said cathodes and spaced therefrom, said members being bodily separate and distinct, and a shielding plate interposed between said members.

3. A unitary electron discharge device comprising an evacuated vessel enclosing a pair of insulating members having marginal flanges, a heating filament wound upon each member between the flanges, a cathode carried by each member and supported upon the flanges of the corresponding members, a shielding plate located between the members, and an anode surrounding each cathode.

4. A unitary electron discharge device comprising an evacuated vessel enclosing an insulating member, a pair of heating fila-

ments wound upon said member in spaced relation, a cathode positioned adjacent each filament and held by said member in spaced relation to the corresponding filament, and an anode surrounding each cathode.

5. A unitary electron discharge device comprising an evacuated vessel enclosing an insulating member having two portions mounted in axial alignment with a groove formed between them, each portion having end flanges, a heating filament wound between the end flanges of each of said portions, a sheet metal cathode surrounding each portion and carried at opposite ends by the flanges of said portions, a shield plate located within the said groove and projecting outwardly from said member, and an anode surrounding each cathode.

6. A unitary rectifier and current limiting device for supplying constant value unidirectional current from alternating current, said device comprising an evacuated vessel, an anode, a cathode positioned adjacent said anode, a second anode, means for connecting said second anode with said cathode, a second cathode positioned adjacent said second anode, and heating means for said second cathode adapted for energization by alternating current.

7. A unitary rectifier and current limiting device comprising an evacuated vessel, an anode, a cathode positioned adjacent said anode, a second anode, means for connecting said second anode with said cathode, a second cathode positioned adjacent said second anode, heating means for said cathodes adapted for energization by alternating current, an input terminal connected to the first mentioned anode, an output terminal connected to said second mentioned cathode, and terminals connected to said heating means, all of said terminals leading outwardly through the walls of said vessel.

In testimony that I claim the foregoing I have hereunto set my hand at Milwaukee, in the county of Milwaukee and State of Wisconsin.

ARISTOTE MAVROGENIS.
